[57] CLAIM

The ornamental design for a bicycle control lever, as shown.

DESCRIPTION

FIG. 1 is a perspective view of a bicycle control lever in accordance with the design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof.

FIG. 7 is a right side elevational view thereof; and

FIG. 8 is a perspective view thereon on a reduced scale mounted on a bicycle frame which is shown in broken lines for illustrative purposes only and forms no part of the claimed design.

FIG. 1

FIG. 2

FIG. 3

FIG. 4

FIG. 5

FIG. 7

FIG. 6
